FAUCET

Nathan Roach, Cleveland, Ohio, assignor to The
Cleveland Brass Manufacturing Company,
Cleveland, Ohio, a corporation of Ohio

Application September 16, 1941, Serial No. 411,057

1 Claim. (Cl. 225—44)

This invention relates to improvements in faucets, particularly of a type built into and forming part of a bung or closure member for a barrel, drum or similar container.

An object of the present invention is to provide a combined bung and valve wherein the body of the bung itself forms a portion of the valve and the entire device is composed of a few parts simply constructed but efficient to carry out its purpose. The advantages of the invention will be more apparent from the accompanying drawing and description and the essential features will be set forth in the claim.

In the drawing, Fig. 1 is a central sectional view through one form of my device, the view being taken generally along the line 1—1 of Fig. 4; Fig. 2 is a similar view showing a slightly modified form of construction; Fig. 3 is a side elevation of the device of Fig. 2; while Fig. 4 is a front elevation of the device of Fig. 3.

In Fig. 1, the bung 10 is provided with a thread at 11 for connection with a similar coating thread formed in the walls about the bunghole of a barrel, drum or similar container. Combined with this bung is a valve for dispensing the contents of the container to which the bung is attached. For this purpose, formed integrally with or at least rigid with the central portion of the bung is a sleeve 12, the inner walls of which define a passageway through the bung for the passage of the contents of the container to the outside. The inner end of the sleeve 12 is formed at 12a to provide a valve seat.

A second sleeve 13 is fitted snugly within the sleeve 12 and adapted to reciprocate therein. The inner end of this sleeve is provided with a valve 14 adapted to coact with the valve seat 12a. In the form shown in Fig. 1, a projection 13a on the inner end wall 13b of the sleeve 13 serves to hold a valve sealing gasket 14a outside of which is a plate 14b, all held together by riveting over the end of the stud 13a. Suitable openings 15 near the inner end of sleeve 13 are provided to permit the entrance of liquid from the container into the sleeve 13 when the valve is open as indicated in Fig. 1. A helical spring 16 surrounds a reduced diameter of the sleeve 13 and acts between the shoulder 17 of sleeve 12 and the shoulder 18 of sleeve 13 to urge valve 14 toward its seat.

The outer end of sleeve 13 is preferably formed as at 19 to provide a faucet discharge spout which is preferably short so that it will lie close to the container. The end of the spout may be provided with a thumb piece 20 or other means for push-

ing the sleeve 13 inwardly so as to open the valve 14.

The modification shown in Fig. 2 is similar to that shown in Fig. 1 except for the manner of securing the valve on the inner end of sleeve 13. Here the inner end of sleeve 13 is provided with a thread 21 into which is threaded an assembled valve 22 which comprises a gasket 22a adapted to coact with the valve seat 12a, a metal holding plate 22b and a noncircular head 22c by which the valve may be rotated to engage the threads 21. This type of valve is more readily replaced than the type shown in Fig. 1.

As best seen in Figs. 3 and 4, a very simple means is provided for holding the valve closed. On the outer end of sleeve 12 is formed a spiral cam 23 which extends from a low point at 23a to a high point at 23b. A pin 24 rigidly attached to sleeve 13 is adapted to enter a longitudinally extending slot 25 in sleeve 12 when it is desired to open the valve by pushing on the thumb piece 20. When the valve is to be locked closed the spout 19 is rotated, thus carrying the pin 24 from the position shown in Figs. 3 and 4 in a clockwise direction as viewed in Fig. 4 about the cam surface 23 until the pin 24 holds the valve 14 firmly on its seat. Because of the comparatively flat surface on the cam 23 the valve will remain in this locked position. A gasket 26 of leather or the like may be placed between shoulder 18 and spring 16 to prevent liquid leakage between sleeves 12 and 13.

It is obvious that a steel drum or the like provided with my improved combined bung and faucet in one of the end heads of the drum may utilize the faucet for dispensing the contents of the drum and when it is necessary to move the drum the faucet may be locked by means of the pin 24 and the cam 23, whereupon the drum may be rolled about without danger of losing any of its contents. The closed position of the valve is shown in Fig. 2 and the open position of the valve in Fig. 1.

What I claim is:

45 In combination, a bung having a threaded cylindrical wall for engagement with the wall of a container bunghole, a sleeve forming part of said bung and located centrally thereof spaced from said cylindrical wall, there being an opening 50 through said bung in registration with the hollow portion of said sleeve, a valve seat on the container-facing side of said bung surrounding said opening, a second sleeve snugly reciprocable within said first sleeve, a faucet discharge spout 55 on the outer end of said second sleeve, a valve

on the inner end of said second sleeve adapted to coact with said seat and movable into said container by reciprocation of said second sleeve relative to said first sleeve, spring means between said sleeves urging said valve toward engagement with said seat, a pin extending radially outwardly from said second sleeve, and a spiral cam on said first sleeve adapted to engage said pin and

5 by rotation of said second sleeve to cam said pin and therefore said valve outwardly against said seat to hold said valve closed, said cam at its end nearer the container communicating with a slot extending longitudinally of said first sleeve thus permitting reciprocation of said second sleeve to open said valve.

NATHAN ROACH.
